US0D1049626S

(12) **United States Design Patent** (10) **Patent No.:** **US D1,049,626 S**
(45) **Date of Patent:** **** Nov. 5, 2024**

(54) **CONTACT LENS CONTAINER**

(71) Applicant: **PEGAVISION CORPORATION**,
Taoyuan (TW)

(72) Inventors: **Yi-Fang Huang**, Taoyuan (TW);
Po-Chun Chen, Taoyuan (TW)

(73) Assignee: **PEGAVISION CORPORATION**,
Taoyuan (TW)

(**) Term: **15 Years**

(21) Appl. No.: **29/843,482**

(22) Filed: **Jun. 21, 2022**

(30) **Foreign Application Priority Data**

May 25, 2022 (TW) 111302508

(51) **LOC (14) Cl.** **03-01**

(52) **U.S. Cl.**

USPC **D3/264**; D9/732

(58) **Field of Classification Search**

USPC D3/207, 215, 219, 229, 263–266, 301;
D12/417; D16/330, 339; 24/3.3, 3.7,
24/3.8, 563; 206/5, 5.1, 6; 248/902;
351/112, 155; D9/414, 416, 732
CPC A45C 11/04; A45C 11/005; A47F 7/02;
A47F 7/021

See application file for complete search history.

(57) **CLAIM**

The ornamental design for a contact lens container as shown
and described.

DESCRIPTION

FIG. 1 is a front, top, left perspective view of a contact lens
container, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, front, right perspective view thereof.
The dashed broken lines in the drawing depict portions of
the contact lens container that form no part of the claimed
design.

1 Claim, 8 Drawing Sheets
